UNITED STATES PATENT OFFICE.

FRANZ BORSODI, OF MAGYAR-BÁNHÉGYES, AUSTRIA-HUNGARY.

ELECTROTHERAPEUTIC APPARATUS.

SPECIFICATION forming part of Letters Patent No. 538,764, dated May 7, 1895.

Application filed October 22, 1888. Serial No. 288,760. (No model.) Patented in England September 1, 1886, No. 11,529; in Belgium September 15, 1886, No. 74,477; in Austria-Hungary March 17, 1887, No. 5,105 and No. 5,199, and in France August 13, 1887, No. 178,536.

To all whom it may concern:

Be it known that I, FRANZ BORSODI, a subject of the Emperor of Austria-Hungary, and a resident of Magyar-Bánhegyes, Hungary, in the Austro-Hungarian Empire, have invented a new and useful Electric Apparatus for Treatment of Diseased Human Muscles and Nerves, (for which I have obtained Letters Patent in England September 1, 1886, No. 11,529; in Belgium September 15, 1886, No. 74,477; in Austria-Hungary March 17, 1887, No. 5,105 and No. 5,199, and in France August 13, 1887, No. 178,536;) and I do hereby declare that the following is a full, clear, and exact description of the same.

This invention relates to an electrical appliance, designed to be worn on the person, for the purpose of beneficially affecting the parts which are in contact; and it is specially intended for strengthening and aiding the nerves.

In the accompanying drawings, forming a part of this specification, Figure 1 is a side elevation of an electrical device embodying improvements. Fig. 2 is a central longitudinal section of the same. Fig. 3 is a central vertically-transverse section, and Fig. 4 is a plan view.

The improved device consists of two concave plates *a a* together forming a central recess *c* within which is arranged a voltaic pile,

essentially formed of thin copper and zinc rods, having an insulating covering of varnish. The ends of the metal bail *g* are bent inward to engage the upper loop portion *f* of the plates. The side ends of the bail *g* are connected by wires *h* with the voltaic pile.

The apparatus described is worn close to the body and in the locality of the part affected. The said apparatus is preferably held in position by means of a cord *j* which passes through the same and permits its attachment to the person by the wearer.

In use, the current generated by the voltaic pile, is transmitted to the bail *g* by wires *h*.

The concave form of the plates *a a* insures the device accommodating itself to the curvature of the body of the wearer.

I claim—

In an electro-therapeutical apparatus, the combination with the plates *a a* secured together, to form a recess *c*, a voltaic pile located in said recess, and a bail *g* secured to said plates and electrically connected with the voltaic pile by wires *h*, substantially as set forth.

In witness whereof I have hereunto signed my name in the presence of two subscribing witnesses.

FRANZ BORSODI.

Witnesses:

AKOSMICHAJLOVITT,
WACHSLER SALENISKY.
